MEANS FOR SECURING AWNING FABRIC TO
AWNING ROLLERS

Errol P. D'AZZO, New York, N. Y.

Application March 12, 1952, Serial No. 276,170

8 Claims. (Cl. 160—404)

1

This invention relates to new and useful improvements in means for securing an awning fabric to an awning roller and the present application is a continuation-in-part of my earlier application Serial No. 169,204, filed June 20, 1950.

Prior to the present invention, it has been customary to construct awning rollers to have inner spool bodies of wood or the like with a sheet metal sheath engaged thereabout. The meeting longitudinal edges of the sheath have been turned inward and secured to the spool body by headed nails driven between the ends with the same nails being used to secure the awning fabric to the spool. Such construction has been found objectionable because removal of the nails to free the awning fabric to be replaced also released the ends of the sheath with the result that replacement of the fabric was accompanied by release of the sheath requiring that it be re-anchored in position together with the new awning fabric.

The present invention proposes an improvement of the prior art constructions in which the metal sheath is anchored to the spool body independently of the awning fabric so that when the fabric is being removed to be replaced, the sheath is not also freed to thereby eliminate the objection to the prior art construction.

As a further object, the present invention proposes modifications of the present invention which adopt the developments of the present improvement to awning rollers whether they have spool bodies formed of wood or metal.

Still further, the present invention proposes joining the meeting edges of the metal sheath by an inturned seam fitted against a flat surface formed on the wooden spool body or fitted into a longitudinally extended groove formed in the metal spool body to thereby, in addition to joining the longitudinal meeting edges, hold the metal sheath against turning relative to the spool body.

The present invention further proposes forming the spool body with a longitudinally extended groove into which the metal sheath has a portion fitted so as to form a longitudinally extended outwardly opening channel in a manner to receive anchor means inserted through the awning fabric and thereby independently secure the awning fabric to the roller.

It is a further object of the present invention to provide means for securing an awning fabric to an awning roller which is simple and durable, which is effective for its intended purpose and which can be applied to awning constructions without materially increasing the cost thereof.

2

For further comprehension of the invention, and of the objects and advantages thereof, reference will be had to the following description and accompanying drawing, and to the appended claims in which the various novel features of the invention are more particularly set forth.

On the accompanying drawing forming a material part of the present disclosure:

Fig. 1 is a detailed elevational view of the end of an awning roller constructed in accordance with the present invention.

Fig. 2 is a partial longitudinal sectional view taken on the line 2—2 of Fig. 1.

Fig. 3 is a transverse sectional view taken on the line 3—3 of Fig. 2.

Fig. 4 is a perspective view of the end of the awning roller shown in Figs. 1 to 3.

Fig. 5 is a view similar to Fig. 3, but illustrating a modification of the present invention.

The awning, according to the first form of the present invention shown in Figs. 1 to 4, includes an awning roller 10 to which a longitudinal edge of an awning fabric 11 is secured. The awning roller 10 includes an elongated inner spool body 12 shaped of wood to have a circular cross-section as shown in Figs. 3 and 4. The two ends of the roller 10 are alike in construction differing only in the fact that the one end—the end shown in Fig. 1—is connected to mechanism for turning the roller in one direction or the other to wind and unwind the awning fabric 11. At each end, the inner spool body 12 is formed with a transverse slot 14 into which there is fitted the transverse rib 15 integrally formed with an end cap 16 fitted onto the respective end of the spool body 12. The end caps 16 are secured in position by means of nails 17 inserted through holes formed in the end caps and hammered into the material of the spool body 12.

The outer faces of the end caps 16 are formed with concentric tubular bosses 18 into which the inner ends of end aligned trunnions 19 are inserted. The trunnions 19 are retained in position by means of bolts 20 which pass through the bosses 18 and the trunnions 19 at right angles to the axes of the trunnions 19.

The trunnion 19 at the end of the awning roller 10 shown in Fig. 1, is received within a gear box 21 which is fixedly mounted on a wall and has a depending rotative hook 22 for engagement by the usual crank handle, not shown. The trunnion 19 at the other end of the awning roller, not shown on the drawing, is rotatively supported in a suitable wall bracket, so that rotations of the crank handle in one direction or

the other will cause similar rotation of the awning roller 10 to wind and unwind the awning fabric 11.

An elongated sheet of metal is engaged about the spool body 12, between the inner faces of the end caps 16, forming a metal sheath or covering 23 for the spool body. The meeting longitudinal edges of the metal sheath 23 are joined together by an inwardly turned seam 24, see Figs. 2 and 3. To accommodate the seam 24, without interrupting the roundness of the awning roller 10, the side of the spool body 12 at the seam 24 is formed with a flat side 25. The flat side 25 is of sufficient depth to be abutted by the seam 24 and so maintain the sheath 23 against rotative movement about the spool body 12.

The means for attaching the longitudinal edge of the awning fabric 11 to the awning roller 10 is characterized by the fact that the spool body 12, diametrically opposite the seam 24, is formed with a longitudinally extended groove 26. The sheath 23 has a portion 27 bent into and conformed to the shape of the groove 26 to thereby form an outwardly opening longitudinally extended channel 28. The longitudinal edge of the awning fabric 11 is folded upon itself to be two-ply and is extended across the open side of the channel 28 and anchor means are provided for insertion through the awning fabric and into the channel 28 to secure the awning fabric in position. The anchor means is characterized by elongated nails 29 which have their shanks inserted through the two plies of the awning fabric and pressed into the channel 28 at spaced positions along the length thereof. The nails 29 are spaced along the length of the channel 28 and have enlarged heads 30 bearing against the outer face of the awning fabric 11. The shanks of the nails 29 are of a diameter just slightly greater than the width of the channel 28 so as to have a force fit within the channel to be frictionally retained in position.

From the foregoing description, it is apparent that the attachment of the awning fabric 11 and the attachment of the metal sheath 23 are independent of each other so that removal of the awning fabric for replacement does not release the metal sheath from its connection with the spool body 12.

In the modification of the invention shown in Fig. 5, the construction of the awning roller 10' is characterized by a spool body 12' formed of metal. In this form of the invention, the seam 24 which joins the longitudinal meeting edges of the metal sheath 23, is received within a longitudinally extended groove 25' formed in the spool body 12' diametrically opposite the groove 26.

A slightly different arrangement is also provided for anchoring the end of the awning fabric 11 in position. In this form of the invention, the longitudinal edge of the awning fabric 11' which is anchored in position is left unfolded to be of one-ply thickness. The anchor means is characterized by self-tapping screws 29' which have threaded shanks inserted through the awning fabric 11' and threaded into the channel 28. The screws 29' have enlarged heads 30' which bear against the outer face of the awning fabric.

The shanks of the self-tapping screws 29' are of a diameter just slightly greater than the width of the channel 28 so that when they are tightened into position they will cut threads in the opposed walls of the channel and thereby cause the screws to be securely anchored in the channel.

In all other respects, the form of the invention shown in Fig. 5 is similar to that described

in connection with Figs. 1 to 4 and like reference numerals are used to identify like parts.

While I have illustrated and described the preferred embodiments of my invention, it is to be understood that I do not limit myself to the precise constructions herein disclosed and the right is reserved to all changes and modifications coming within the scope of the invention as set forth in the appended claims.

Having thus described my invention, what I claim as new and desire to secure by United States Letters Patent is:

1. An awning roller to which is secured an awning fabric, comprising an elongated inner spool body, an elongated metal sheet bent about said spool body to form a sheath therefor, means securing together the meeting longitudinal edges of said sheet of metal to thereby hold said sheath against rotation with relation to said spool body, said spool body having a longitudinally extended groove in one side thereof, said sheath having a portion fitted into said groove forming a longitudinally extended outwardly opening channel, and anchor means inserted through the awning fabric and received within said channel securing the awning fabric to the roller, said spool body being formed of wood, said wooden spool body having a flat side diametrically opposite said groove, said securing means comprising an inturned seam formed along said meeting edges and abutted against said flat side.

2. An awning roller to which is secured an awning fabric, comprising an elongated inner spool body, an elongated metal sheet bent about said spool body to form a sheath therefor, means securing together the meeting longitudinal edges of said sheet of metal to thereby hold said sheath against rotation with relation to said spool body, said spool body having a longitudinally extended groove in one side thereof, said sheath having a portion fitted into said groove forming a longitudinally extended outwardly opening channel, and anchor means inserted through the awning fabric and received within said channel securing the awning fabric to the roller, said spool body being formed of wood, said wooden spool body having a flat side diametrically opposite said groove, said securing means comprising an inturned seam formed along said meeting edges and abutted against said flat side.

3. An awning roller to which is secured an awning fabric, comprising an elongated inner spool body, an elongated metal sheet bent about said spool body to form a sheath therefor, means securing together the meeting longitudinal edges of said sheet of metal to thereby hold said sheath against rotation with relation to said spool body, said spool body having a longitudinally extended groove in one side thereof, said sheath having a portion fitted into said groove forming a longitudinally extended outwardly opening channel, and anchor means inserted through the awning fabric and received within said channel securing the awning fabric to the roller, said spool body being formed of wood, said wooden spool body having a flat side diametrically opposite said groove, said securing means comprising an inturned seam formed along said meeting edges and abutted against said flat side, said anchor means comprising nails having enlarged heads and shanks inserted through the awning fabric and extended into said channel, said awning fabric being folded upon itself to be of two-ply thickness where the shanks of said nails are inserted.

4. An awning roller to which is secured an awning fabric, comprising an elongated inner spool body, an elongated metal sheet bent about said spool body to form a sheath therefor, means securing together the meeting longitudinal edges of said sheet of metal to thereby hold said sheath against rotation with relation to said spool body, said spool body having a longitudinally extended groove in one side thereof, said sheath having a portion fitted into said groove forming a longitudinally extended outwardly opening channel, and anchor means inserted through the awning fabric and received within said channel securing the awning fabric to the roller, said spool body being formed of wood, said wooden spool body having a flat side diametrically opposite said groove, said securing means comprising an inturned seam formed along said meeting edges and abutted against said flat side, said anchor means comprising nails having enlarged heads and shanks inserted through the awning fabric and extended into said channel, said awning fabric being folded upon itself to be of two-ply thickness where the shanks of said nails are inserted.

5. An awning roller to which is secured an awning fabric, comprising an elongated inner spool body, an elongated metal sheet bent about said spool body to form a sheath therefor, means securing together the meeting longitudinal edges of said sheet of metal to thereby hold said sheath against rotation with relation to said spool body, said spool body having a longitudinally extended groove in one side thereof, said sheath having a portion fitted into said groove forming a longitudinally extended outwardly opening channel, and anchor means inserted through the awning fabric and received within said channel securing the awning fabric to the roller, said spool body being formed of wood, said wooden spool body having a flat side diametrically opposite said groove, said securing means comprising an inturned seam formed along said meeting edges and abutted against said flat side, said anchor means comprising nails having enlarged heads and shanks inserted through the awning fabric and extended into said channel, said awning fabric being folded upon itself to be of two-ply thickness where the shanks of said nails are inserted.

6. An awning roller to which is secured an awning fabric, comprising an elongated inner spool body, an elongated metal sheet bent about said spool body to form a sheath therefor, means securing together the meeting longitudinal edges of said sheet of metal to thereby hold said sheath against rotation with relation to said spool body, said spool body having a longitudinally extended groove in one side thereof, said sheath having a portion fitted into said groove forming a longitudinally extended outwardly opening channel, and anchor means inserted through the awning fabric and received within said channel securing the awning fabric to the roller, said spool body being formed of wood, said wooden spool body having a flat side diametrically opposite said groove, said securing means comprising an inturned seam formed along said meeting edges and abutted against said flat side, said anchor means comprising nails having enlarged heads and shanks inserted through the awning fabric and extended into said channel, said awning fabric being folded upon itself to be of two-ply thickness where the shanks of said nails are inserted.

shanks inserted through the awning fabric and extended into said channel, the shanks of said nails having a diameter slightly greater than the width of said channel to have a force frictional fit in said channel.

4. An awning roller to which is secured an awning fabric, comprising an elongated inner spool body, an elongated metal sheet bent about said spool body to form a sheath therefor, means securing together the meeting longitudinal edges of said sheet of metal to thereby hold said sheath against rotation with relation to said spool body, said spool body having a longitudinally extended groove in one side thereof, said sheath having a portion fitted into said groove forming a longitudinally extended outwardly opening channel, and anchor means inserted through the awning fabric and received within said channel securing the awning fabric to the roller, said spool body being formed of metal, said metallic spool body having a second groove diametrically opposite said first groove, said securing means comprising an inturned seam formed along said meeting edges and inserted into said second groove.

5. An awning roller to which is secured an awning fabric, comprising an elongated inner spool body, an elongated metal sheet bent about said spool body to form a sheath therefor, means securing together the meeting longitudinal edges of said sheet of metal to thereby hold said sheath against rotation with relation to said spool body, said spool body having a longitudinally extended groove in one side thereof, said sheath having a portion fitted into said groove forming a longitudinally extended outwardly opening channel, and anchor means inserted through the awning fabric and received within said channel securing the awning fabric to the roller, said spool body being formed of metal, said metallic spool body having a second groove diametrically opposite said first groove, said securing means comprising an inturned seam formed along said meeting edges and inserted into said second groove, said anchor means comprising self-tapping screws having enlarged heads and threaded shanks inserted through the awning fabric and extended into said channel.

6. An awning roller to which is secured an awning fabric, comprising an elongated inner spool body, an elongated metal sheet bent about said spool body to form a sheath therefor, means securing together the meeting longitudinal edges of said sheet of metal to thereby hold said sheath

against rotation with relation to said spool body, said spool body having a longitudinally extended groove in one side thereof, said sheath having a portion fitted into said groove forming a longitudinally extended outwardly opening channel, and anchor means inserted through the awning fabric and received within said channel securing the awning fabric to the roller, said spool body being formed of metal, said metallic spool body having a second groove diametrically opposite said first groove, said securing means comprising an inturned seam formed along said meeting edges and inserted into said second groove, said anchor means comprising self-tapping screws having enlarged heads and threaded shanks inserted through the awning fabric and extended into said channel, said threaded shanks of said self-tapping screws being of a diameter slightly greater than the width of said channel to cut threads in the side walls of the channel as the screws are tightened into position.

7. In combination, an awning roller comprising a metal tube having a preformed longitudinal U-shaped and inset channel and wood core plugs formed with mating channels and snugly fitted in the tube, the U-shaped longitudinal channel having parallel side walls and having a mouth normally open the full length of the channel and the channel extending for the length of the tube and roller, and metal end caps fitted on the ends of the preformed tube and coupled to the wood cores, the side walls of the U-shaped channel being relatively close to each other, and adapted to snugly receive fastener pins driven into the channel against the resistance of said side walls and the compressive resistance of the enclosed wood core plug, the wood core plug having a longitudinal channel to snugly receive the U-channel.

8. The combination set forth in claim 7, including awning fabric fastening pins wider than the space between the side walls of the U-shaped channel.

ERROL P. D'AZZO.
